(57) **CLAIM**

The ornamental design for a power source for a dental instrument, as shown and described.

DESCRIPTION

FIG. 1 is a top front perspective view of a power source for a dental instrument showing the claimed design;

FIG. 2 is a bottom rear perspective view thereof;

FIG. 3 is a rear view thereof;

FIG. 4 is a front view thereof;

FIG. 5 is a right side view thereof, the left side view being a mirror image thereof;

FIG. 6 is a top view thereof; and,

FIG. 7 is a bottom view thereof.

The broken lines in the figures show portions of the power source for a dental instrument that form no part of the claimed design.

The dot-dash broken lines in the figures show boundaries that form no part of the claimed design.

1 Claim, 3 Drawing Sheets
